LOOM

Margaret Bergman, Poulsbo, Wash.

Application June 5, 1935, Serial No. 25,150

3 Claims. (Cl. 139—29)

This invention relates to looms, and has for one of its principal objects the production of a simple loom structure which may be folded into a compact space thereby facilitating transportation of the loom from house to house, or place to place.

Another object of this invention is the provision of a simple means by which the loom may be collapsed and later set-up at a place of operation without necessitating a great amount of skill.

A still further object of this invention is the production of a simple and efficient folding loom wherein the warp may be put in and weave started before the loom is folded for shipment.

Other objects and advantages will appear throughout the following specification and claims.

In the drawings:—

Figure 1 is a side elevation of the loom in a set-up position;

Figure 2 is a top plan view, certain parts being broken away and shown in section;

Figure 3 is a top plan view of the loom, certain parts being removed prior to folding;

Figure 4 is a top plan view of the loom in its folded position;

Figure 5 is a section taken on line 5—5 of Figure 4 showing the loom in its folded position;

Figure 6 is a section taken on line 6—6 of Figure 5;

Figure 7 is a front elevation of the loom in a set-up position;

Figure 8 is a rear elevation of the loom in a set-up position;

Figure 9 is a front elevation of the loom in a folded position;

Figure 10 is a rear elevation of the loom in a folded position.

By referring to the drawings, it will be seen that 15 designates the main frame which consists of a pair of side sections 16 which are similarly constructed. These side sections 16 are adapted to extend in a vertical position and support the conventional loom mechanism embodying a warp beam or bar 17 and a cloth beam 18 which may be pushed back as is shown in Figure 1, when the loom frame is folded.

It should be borne in mind that the present invention relates to the structure of a folding loom frame and any suitable or desired loom mechanism may be associated therewith without departing from the spirit of the invention.

The main frame 15 carries a front folding frame consisting of folding side members 19 which are vertically hinged as at 20 to the front

edge of the main frame 15.—Note particularly Figure 3. Each front side frame 19 is provided with a forward upright 21 having a dove-tail socket 22 formed at its upper extremity, and a transversely extending breast beam 23 spans the distance between the forward side frames 19 for holding these side frames in set-up extended position, such as is shown in Figure 2. This breast beam 23 is provided with dove-tail tongues 24 which releasably fit within the sockets 22 thereby permitting the breast beam to be easily removed from engagement with the front or forward side frames 19 prior to being folded. The front or forward side frames 19 are provided with forwardly extending bottom rails 25, which bottom rails 25 are provided with extending ends 26 projecting beyond the forward uprights 21. A detachable treadle bar 27 rests upon the forward ends 26 and this treadle bar is detachably held in engagement with the forward extensions 29 through the medium of an interfitting pin connection and socket 28. The treadle bar 27 which supports the treadle 29 of a conventional type is in this way removable from the forward or front side sections 19, thereby permitting the side sections 19 to be folded in the direction of the arrows shown in Figure 3.

A rear folding frame 30 is vertically hinged to the main frame and consists of a pair of similarly constructed side sections 31, which side sections are hinged to the main frame 15 by the vertically extending hinges 32. Each rear side frame 31 is provided with a rear upright 33 having an upwardly extending end portion 34 which is notched, as at 35, upon its rear face for receiving the warp bar 36, the ends of which are notched, as at 37, and fit into the sockets 35. Pins 38 are carried by the respective ends of the warp bar 36 for detachably fitting into suitable sockets formed in the uprights 33, as will be obvious by considering the drawings.

From the foregoing description it will be seen that a very simple folding loom frame has been provided, certain parts of which may be readily detached for the purpose of permitting other parts to be conveniently folded and thereby allow the frame to be accommodated in a minimum amount of space. At the same time, it should be understood that certain portions of the frame may be extended and other parts assembled to provide an efficient loom frame possessing the characteristics of the conventional loom and permitting the same functions to be performed. It is not desired to limit the present application to any particular type of loom mechanism.

When it is desired to use the loom, the main frame is set-up in a vertical position, such as is shown in Figure 1, and the forward and rear frames 19 and 30 respectively are moved to an extended position whereby the side frames 19 and 31 may extend at right angles to the front and rear faces of the main frame 15 and the treadle bar, breast beam, and warp bar may then be placed in proper position as is shown in Figures 1 and 2. The loom will then be in its set-up position ready for operation, and the treadles 29 may be connected in the conventional manner. Due to the type of structure illustrated it will be seen that the present loom frame is especially adapted for transportation from one place to another and may be used for demonstrating purposes as well as for the purpose of giving instructions with respect to the operation of the loom and with respect to weaving.

Also because of the present structure and the fact that the main operating parts may be carried by the main frame 15, as illustrated, (note Figure 5), the warp may be placed in the loom and the weave started before the loom is folded and shipped.

When it is desired to fold the loom frame, the treadle bar 27, the breast beam 23, and the warp bar 36 are released, and the end frames 19 and 31 will fold inwardly toward the main frame 15, as indicated in Figure 3, and the treadles 29, the treadle bar, breast beam, and warp bar may be tied together or carried in any suitable or desired manner. When the loom frame is folded, it will require only about one-third of the space which is necessary when the loom is set-up.

By noting particularly Figure 1, it will be observed that the warp bar or beam 36 is placed above or on top of the rear side frames 21, thereby facilitating the adjustment of the cords under the beam or bar. This is accomplished by loosening the ratchet wheel and the bar that holds the warp may be pulled out and placed on top of the loom while assembling or placing the loom in a set-up position. The conventional beater may be hung from the top or in any convenient or suitable manner.

It should be understood that certain detail changes in the mechanical structure, combination or arrangement of parts may be employed without departing from the spirit of the invention, so long as such changes fall within the scope of the appended claims.

Having described the invention, what is claimed as new is:

1. In a loom, a main frame, front side sections constituting a front frame vertically hinged to said main frame at sides thereof and adapted to be folded towards each other across the front of said main frame, rear side sections constituting a back frame vertically hinged to said main frame at sides thereof and adapted to be folded towards each other across the rear of said main frame, detachable transverse bracing means for the front and rear side sections for holding the sections in extended relation, a warp beam carried by the main frame, and a detachable treadle bar carried by the bracing means for said front frame.

2. In a loom, a main frame, front side sections constituting a front frame vertically hinged to said main frame at sides thereof and adapted to be folded towards each other across the front of said main frame, rear side sections constituting a back frame vertically hinged to said main frame at sides thereof and adapted to be folded towards each other across the rear of said main frame, a detachable cross bar for the warp and constituting a brace for the rear side sections, a detachable breast beam engaging the front side sections and constituting a transverse brace, a detachable treadle bar carried by and extending rearwardly from the breast beam of the front side sections, and a cloth beam carried by said main frame.

3. In a loom, a main frame, front side sections constituting a front frame vertically hinged to said main frame at sides thereof and adapted to be folded towards each other across the front of said main frame, rear side sections constituting a back frame vertically hinged to said main frame at sides thereof and adapted to be folded towards each other across the rear of said main frame, a detachable cross bar for the warp and constituting a brace for the rear side sections, a detachable breast beam engaging the front side sections and constituting a transverse brace, a detachable treadle bar carried by the breast beam of the front side sections, a cloth beam carried by said main frame, and the breast beam having interfitting dove-tail connection with the front side sections.

MARGARET BERGMAN.
